MACHINE FOR PRODUCING JAMBS FOR SASH FRAMES

Application filed January 31, 1931. Serial No. 512,605.

This invention relates to woodworking machines and particularly to machines for producing the jambs of window sash frames.

It is the main object of this invention to provide a machine which will make all necessary cuts in boards to rapidly produce completed jambs for window sash frames in quantity with a minimum of labor.

It is a further object to provide a machine which will accomplish this main object while the board being worked on by the machine is clamped in a single fixed position.

Another object is to provide such a machine which will simultaneously make all necessary cuts in a pair of boards to produce a pair of jambs for a window sash frame, one jamb being adapted to be used at the left side of the sash frame and the other jamb being adapted to be used at the right side of the sash frame.

Still another object is to provide a novel and rapidly working mechanism for making the necessary cuts in a pair of boards to produce rectangular openings therethrough such as can be used as the sash weight openings in a pair of jambs of a window sash frame.

It is another object to provide novel and rapidly working mechanism for making the necessary cuts in a pair of boards to produce shouldered openings therethrough, such as can be used as sash weight pulley receiving openings in a pair of jambs of a window sash frame.

One more object is to provide novel and rapidly working mechanism for cutting grooves in a pair of boards to produce such grooves as the mortice grooves in a pair of jambs of a window frame which grooves are adapted to receive the ends of the sills and headers of a window sash frame.

Again a further object is to provide mechanism working in synchronism with said last mentioned mechanism for cutting notches in the edges of the pair of boards to produce such notches in a pair of jambs of a window sash frame as will receive the edges of the sill and headers of the sash frame.

Another object is to combine in a single machine all the mechanisms referred to in

the four last above paragraphs, which mechanisms will all act simultaneously or consecutively on a pair of boards clamped in fixed position to rapidly produce with a minimum of physical labor a completed pair of jambs for a window sash frame.

These and other objects and advantages of the present invention will more fully appear from the following description made in connection with the accompanying drawings, wherein like reference characters refer to the same or similar parts throughout the various views and in which,

Fig. 1 is a view in side elevation illustrating the complete assembled machine;

Fig. 2 is a vertical section taken on the line 2—2 of Fig. 1, as indicated by the arrows;

Fig. 3 is a vertical section taken on the line 3—4 of Fig. 1, as indicated by the lower arrow adjacent the numeral 3;

Fig. 4 is a vertical section taken on the line 4—3 of Fig. 1, as indicated by the upper arrow adjacent the numeral 4;

Fig. 5 is a view taken chiefly in vertical section on the line 5—5 of Fig. 1, as indicated by the arrows;

Fig. 6 is a vertical section taken on the line 6—6 of Fig. 2, as indicated by the arrows;

Fig. 7 is a vertical section taken on the line 7—7 of Fig. 2, as indicated by the arrows;

Fig. 8 is a horizontal section taken on the line 8—8 of Fig. 5, as indicated by the arrows;

Fig. 9 is a vertical section taken on the line 9—9 of Fig. 5, as indicated by the arrows;

Figs. 10, 11 and 12 are illustrative plan views showing in full and dotted lines certain of the various positions that the saws of the mechanism illustrated chiefly in Figs. 3 and 4 will assume during operation;

Fig. 13 is a view illustrating the inner face of a jamb for window sash frames that may be produced by use of the present machine;

Fig. 14 is a section taken on the line 14—14 of Fig. 13 as indicated by the arrows; and

Fig. 15 is a section taken on the line 15—15 of Fig. 13, as indicated by the arrows.

The machine of the present invention may, in general, be considered to comprise a bed

A, clamps B, groove cutting mechanism C, groove cutting mechanism D, notch cutting mechanism E, notch cutting mechanism F, boring mechanism G and rectangular opening cutting mechanism H. The clamps B are used to hold a pair of boards from which a pair of oppositely disposed jambs for window sash frames are to be made in parallel oppositely disposed fixed relation on the bed 5 A, while the various mechanisms C, D, E, F, G and H may act on the boards to make the necessary cuts therein to produce the two sash frame jambs. In describing the machine, it will be necessary to refer to the relative location of various parts on the machine and it is therefore desirable to name the sides and ends of the machine. The near side of the machine as viewed in Fig. 1, will be taken to be the front side of the machine, the far 10 side of the machine as viewed in Fig. 1, will be taken to be the rear side of the machine, while the portion of the machine shown at the right side of the sheet, as viewed in Fig. 1, will be taken to be the right or near end of the machine and the portion of the machine 15 adjacent the left side of the sheet as shown in Fig. 1, will be taken to be the left or far end of the machine.

The floor upon which the machine is located 20 may be numbered 16. The bed A is supported on this floor and consists of a pair of long rails 17 mounted in horizontal parallel spaced relation on a number of longitudinally spaced supports 18 which may be 25 of H-shape as shown, the said supports resting on the floor 16 and acting to hold the rails 17 in spaced relation above the floor. The rails 17 are somewhat similar in formation to ordinary railroad rails and have at 30 their lower edges wide outwardly projecting horizontal flanges and narrow inwardly projecting horizontal flanges. At their upper edges the rails have short outwardly projecting flanges and the inner and outer corners of the rails at their upper edges are bevelled at substantially 45° angles, as shown in the vertical sectional views taken through the machine. The rails 17 extend generally 35 longitudinally of the machine and are connected intermediate the two ends of the machine by a pair of longitudinally spaced and transversely extending bars 19 and 20. There are three pairs of clamps B for supporting the boards to be worked on by the machine, which boards may be designated J and K respectively. One pair of clamps B are disposed adjacent the far or left end of the machine, one pair of clamps B are disposed adjacent the central portion of the machine 40 and one pair of clamps B are disposed adjacent the right or near end of the machine. The central pair of clamps B are supported on the bar 19 and, as best shown in Fig. 3, include an upwardly extending standard 21 having a central upwardly projecting rec-

tangular portion at its upper end to which oppositely disposed angles 22 are secured. The standard also has an outwardly disposed relation from the two angles 22 arms forming screw threaded hubs within which 45 screws 23 work. The screws 23 are provided with wheels 24 at their outer ends and have enlarged heads at their inner ends adapted to bear against the boards J and K respectively to tightly press the same 50 against the vertical flanges of the angles 22. Adjacent the forward end of the machine, and adjacent the rear end of the machine there are mounted on the rails 17 carriages 55 and 26 respectively, which carriages respectively support the two groove cutting mechanisms C and D and the carriage 25 supports the pair of clamps B adjacent the left end of the machine and the carriage 26 supports the pair of clamps B adjacent the 60 right end of the machine. The clamps B adjacent the left end of the machine include a standard 27 secured to the carriage 25 and projecting upwardly therefrom and having spaced upwardly projecting arms to which 65 brackets 28 are secured, which brackets project outwardly from the arms of the standard and form screw threaded hubs within which screws 29 similar to the screws 23 work. The screws 29 carry wheels 30 at their outer 70 ends and carry blocks 31 at their inner ends adapted to bear against the respective boards J and K to clamp the boards tightly against the arms of the standard 27. A standard 32 similar to the standard 27 is secured to the carriage 26 and projects upwardly therefrom and has similar upwardly projecting arms. Secured to standard 32 are brackets 33 forming screw threaded hubs spaced from the 75 arms of the standard 32 and within which screws 34 work. The screws 34 carry wheels 35 at their outer ends and blocks 36 at their inner ends adapted to clamp against the respective boards J and K to hold them tightly against the arms of the standard 32. The 80 three sets of clamps B are so disposed that the boards J and K will be clamped in oppositely disposed parallel spaced relation well above the bed A of the machine in horizontal relation.

The groove cutting mechanisms C and D will now be described. These two mechanisms C and D are very similar in construction and in action there are some differences in the relative arrangement of the parts of the two mechanisms. The carriage 25 is mounted for sliding movement on the rails 17 and is adapted to be held in a desired spaced relation from the right end of the machine. For this purpose, a rack 37 is secured to the lower side of the upper outwardly projecting flange of the front rail 17 and the carriage 25 carries an arm 38 which projects downwardly at the forward side of the carriage and has mounted therein a short shaft 39 to which is secured a 130

pinion 40 meshing with the rack 37. The shaft 39 at its outer end is of polygonal formation to receive a wrench for rotating the shaft to cause the carriage 25 and parts carried thereby to be slid longitudinally of the rails 17. Bolted to the carriage 25 at the rear side thereof is a large upstanding guide 41 which is identically similar to a guide 42 bolted to the carriage 26 with the exception that the guide 41 will preferably be vertically disposed, while the guide 42 will preferably be inclined toward the left end of the machine relative to the vertical. To support the guide 42 in this inclined position, a wedge-shaped block 43 is provided which is disposed between the carriage 26 and the guide 42 and to which the guide 42 is bolted at its right end. It may be here stated that the carriage 26 although capable of sliding movement on the rails 17, is preferably permanently fixed on the rails as by means of bolts 44 running through the outwardly projecting flanges at the upper edges of the rails and fitting within screw threaded recesses in the carriage. The guides 41 and 42 are quite heavy in construction and, as best shown in Fig. 8, these guides are of general channel-shape and have triangular-shaped flanges projecting from their inner corners and received in under cut grooves in carriages 45 and 46 mounted respectively for sliding movement on the two guides 41 and 42. The carriages 45 and 46 extend across the forward sides of the guides 41 and 42 and respectively carry electric motors 47 and 48 having armature shafts 49 and 50 respectively. The two motors have brackets 51 and 52 secured thereto and carry suitable electrical switches 53 and 54 for operating the motors. Flexible cables 55 and 56 carrying electrical conductors run to the switches 53 and 54 respectively and from these switches to the respective motors 47 and 48. The armature shaft 49 projects from the motor 47 toward the right end of the machine for a short distance, while the armature shaft 50 for motor 48 projects toward the left end of the machine for a short distance. The said projecting portions of each shaft 49 and 50 has mounted thereon a pair of spaced circular saws 57 and 58 respectively, and between each pair of saws there is mounted on the two shafts gullet saws 59 and 60. Collars 61 and 62 are carried by the two shafts 49 and 50 and nuts 63 and 64 screw threaded on the ends of the shafts 49 and 50, are used to tightly clamp the saws mounted on these shafts against the respective collars 61 and 62. The upper ends of the guides 41 and 42 are bifurcated and have journaled therein shafts 65 and 66 which carry sheaves 67 and 68 over which cables 69 and 70 run. The cable 69 is secured to the carriage 45 and runs downwardly from the sheave 67 and has secured thereto a counter balancing weight 71, while similarly the cable 69 is secured at one end to the carriage 46 and runs downwardly from the sheave 68 and has secured to its other end a counter balancing weight 72. The weights 71 and 72 are used to counter balance the weight of the carriages 45 and 46 and the parts carried thereby, so as to permit the carriages to be raised and lowered readily on the guides 41 and 42. Casings 73 and 74 are secured to the rear portions of the carriages 25 and 26 and the weights 71 and 72 ride upwardly and downwardly against the outer sides of these casings and are prevented from coming in contact with other mechanism that will be later described. The two guides 41 and 42 are provided with large rectangular openings 41a and 42a respectively, and the two carriages 45 and 46 carry on their rear sides brackets 75 and 76, which project through the openings 41a and 42a respectively and are offset rearwardly from the rear sides of the carriages.

Mounted on the floor 16 is an electric motor 77 controlled by a switch 78 mounted on a bracket 79 carried at the right end of the forward rail 17 as best shown in Fig. 1. A flexible cable 80 carrying electrical conductors runs from a source of electricity to the switch 78 and thence to the motor 77. Mounted on the lower outer wide flange of the front rail 17, are two or more brackets 81 carrying grooved rollers on which a rod 82 travels. The rod 82 projects beyond the right end of the machine and carries a pin 83 at its right end which when the rod is slid to the right, will close the switch 78. A spring 84 is secured at one end to the rod 82 and at its other end to the front rail 17 and this spring acts to normally slide the rod 82 to the left to bring the pin 83 out of contact with the switch 78 and thereby break the electric circuit to the motor 77. The rod 82 is equipped with a handle 85. A pair of brackets 86 are bolted to the outer flanges of the two rails to extend below the same, as best shown in Fig. 5, and these brackets have portions extending transversely of the rails and forming bearings for a long shaft 87 extending to a point adjacent the motor 77. The shaft for the motor 77 carries a pinion 88 which meshes with a large gear 89 mounted on the right end of the shaft 87. The brackets 86 have portions forming bearings for two transverse shafts 90 which project beyond the rear rail 17 and extend forwardly to points adjacent the shaft 87. Each shaft 88 carries at its forward end a ring gear 91. It will be noted that one of the brackets 86 is located near the right end of the machine below the groove cutting mechanism D, while the other of the brackets 86 is located adjacent the left end of the machine and below the groove cutting mechanism C. The shaft 87 adjacent its right end carries a bevelled gear 92 which meshes with the ring gear on the shaft 90 adjacent the right end of the machine and the shaft 87 also carries

adjacent its left end a bevelled gear 93 which meshes with the ring gear 91 carried by the shaft 90 adjacent the left end of the machine. The bevelled gear 92 may be fixed to the shaft 87 but the gear 93 will be mounted on the shaft 87 for rotation therewith, but for sliding movement relative to the shaft. For this purpose the shaft 87 is provided with a long slot 87a and the gear 93 carries a cross pin 10 or key which travels within slot 87a. The bevelled gear 93 is slidably mounted on the shaft 87 in order that the left hand bracket 86 may be slid to different positions and secured on the rail 17 so that the spacing of the 15 left hand bracket 86 from the right end of the machine may be varied as the spacing of the groove cutting mechanism C from the right end of the machine is varied. Cranks 94 are secured to the rear ends of the shafts 20 90 and these cranks are connected by crank pins 95 to pitmen 96 connected respectively by crank pins 97 to the brackets 75. It will be seen as the two shafts 90 are rotated through 180° to swing the cranks 94 from 25 a vertical position above the shaft to a vertical position below the shaft, the two carriages 45 and 46 will be lowered from an upwardly raised position with the saws 57-59 and 58-60 above the boards J and K to a 30 position where the said jaws extend below the boards. Similarly, when the shafts 90 are rotated through 180° from a position where the cranks 94 extend downwardly in vertical relation from the shafts to a position where they extend vertically above the shafts, the carriages 45 and 46 will be raised upwardly on the guides to raise the specified saws from a position below the boards J and K to a 35 position above the same. The saws 57-59 and 58-60 will be of such diameter and will be so positioned that these saws will move between the two boards J and K clamped in place by the three sets of clamps, so that the edges of the saws will come in contact with 40 both boards and the saws will thus cut grooves in the boards which extend generally transversely to the boards. The saws of the groove cutting mechanism C will cut grooves in the boards extending directly transversely across 45 the ends of the boards, while the saws of the groove cutting mechanism D due to the inclination of the guide 42 will cut grooves which extend diagonally across the boards. It is desirable when the motor 77 is set in 50 operation by sliding the rod 82 to the right, that the motor remain in operation until the two shafts 90 have been rotated through 180° and then that the motor be put out of operation. In order that this may be accomplished, the rod 82 is angularly bent transversely of the machine at its right end and then downwardly bent as best shown in Fig. 5, and provided at its lower end with a bend 55 extending longitudinally of the machine and towards the left end of the same to form a

dog 82a, as best shown in Fig. 9. A ratchet 98 is mounted on the shaft 90 adjacent the right end of the machine and this ratchet is provided with angular teeth at diametrical points as shown in Fig. 9. As the motor 77 is set in operation, by sliding the rod 82 to the right, the dog 82a formed by the rod will be slid out of engagement with one tooth of the ratchet 98 and the dog 82a will then ride on one circumferential portion of the ratchet 98 until the dog 82a is carried into the notch 70 at the opposite side of the ratchet, whereupon the dog 82a will engage the other shoulder of the ratchet and the spring 84 will cause the rod 82 to slide to the left and thereby open the switch 78 to stop the motor 77. It will, accordingly, be seen that whenever the rod 82 is slid to the right, the motor 77 will be actuated to swing the shafts 90 through 180° and to thereby cause both carriages 45 and 46 80 to be either lowered from an extreme upwardly raised position to an extreme lower position on the guides 41 and 42 or to cause the said carriages to be raised from their extreme lower positions to their extreme raised 90 positions.

The notch cutting mechanism E is constructed to operate in synchronism with the groove cutting mechanism C, while the notch cutting mechanism F is constructed to operate in synchronism with the groove cutting mechanism D. The two carriages 25 and 26 carry on their upper faces transversely extending ribs 25a and 26a respectively, which are oppositely diagonally inclined to form 100 guideways for carriages 99 and 100 respectively mounted thereon. The two carriages 99 and 100 have motors 101 and 102 respectively bolted thereon and the shafts for these motors carry pulleys 103 and 104 respectively 105 over which belts 105 and 106 run. The belts 105 and 106 also run over pulleys 107 and 108 respectively carried by shafts 109 and 110 journaled in bearings 111 and 112 mounted on the carriages 99 and 100 respectively adjacent their rear sides. Secured to the right end of the shaft 109 is a rack saw 113, while secured to the left end of the shaft 110 is a similar rack saw 114, and these rack saws are mounted at such a level as to engage the 110 respective ends of the boards J and K at their lower edges when the carriages 99 and 100 are slid transversely of the bed A. The motors 101 and 102 have electric switches 115 and 116 respectively mounted thereon which 115 control the supply of electricity to the motors and armored cables 117 and 118 carrying electrical conductors respectively run from a source of electricity to the switches 115 and 116 and thence to the two motors 101 and 102. Pivoted to the upper end of the right side of the guide 41 is an arm 119 of angular shape in cross section and a similar arm 120 is pivoted to the upper end of the left side of the guide 42. The two arms 119 and 120 are pref- 125 130

erably bent as best shown in Fig. 5 and have respectively pivoted to their lower ends pitman rods 121 and 122 which rods are pivotally connected respectively at their forward ends to the rear ends of the carriages 99 and 100. The right side of the carriage 45 has an arm 123 secured thereto which projects rearwardly from the carriage beyond the guide 41 and this arm is angularly bent at its rear end to project over the arm 119. The arm 123 carries a pair of spaced roller shafts 124 on which rollers 125 are journalled and one flange of the arm 119 works between the two rollers 125. A similar arm 126 is carried at the left side of the carriage 46 and projects rearwardly beyond the guide 42 and this arm carries short shafts 127 on which rollers 128 are journalled. One flange of the arm 120 works between the two rollers 128. With this construction, it will be seen that as the two carriages 45 and 46 move downwardly on the guides 41 and 42, the arms 123 and 126 will be moved downwardly with the carriages and the rollers 125 and 127 respectively acting on the arms 119 and 120, will swing the lower ends of these arms 119 and 120 forwardly to move the pitman rods 121 and 122 forwardly and thus slide the two carriages 99 and 100 across the carriages 25 and 26 from adjacent the rear side thereof to adjacent the front side thereof. As this is done, the two rack saws 113 and 114 will be moved across the ends of the lower edges of the boards to cause notches to be cut in the same. The action of the pitman rods 121 and 122 is such that before the carriages 45 and 46 are lowered to such a point as to bring the saws 57-29 and 58-60 below the lower edges of the boards, the carriages 99 and 100 will be swung so far forwardly that the saws operated from the motors 47 and 48 cannot come in contact with the rack saws 113 and 114 and the rack saws 112 and 114 will be completely out of the way of movement of the carriages 45 and 46 and the parts carried thereby. It will be understood that when the carriages 45 and 46 are raised, the carriages 99 and 100 will be slid rearwardly to again cause the rack saws 113 and 114 to traverse the lower edges of the boards K and J adjacent the ends thereof. If desired, hoods such as the hood 129 may be applied to the carriages 45 and 46 to partially encompass saws operated from the motors 47 and 48 to prevent saw dust and shavings being scattered by these saws. The hood 129 illustrated is cut away on its edges at its right side and the left side of the hood forms a stop or abutment for the left ends of the boards J and K as they are inserted in place to be clamped by the clamps B. The casings 73 and 74 prevent the counterbalancing weights 71 and 72 from interfering with the action of the cranks 94.

Boring mechanism G will now be described and this mechanism is best illustrated in Figs.

1, 2, 6 and 7. Mounted for longitudinal sliding movement on the two rails 17 to the right of the mechanisms C and E is a carriage 130. This carriage has transverse ribs 130a extending upwardly at inclined and opposite directions formed on its upper surface which form guides for a carriage 131 which is mounted for sliding movement transversely of the bed and of the carriage 130. An electric motor 132 is secured to the carriage 131 adjacent the rear side thereof, and forward of this motor is a gear casing 133 mounted on the carriage 131 and projecting upwardly therefrom between the positions of the boards J and K when clamped in place on the machine. The armature shaft 134 of the electric motor 132 projects forwardly into this gear casing 133 and the forward end of the shaft is journalled in this gear casing. A shaft 135 is journalled in the gear casing 133 above the motor shaft 134 and a large pinion 136 mounted on the motor shaft 134 within the gear casing 133, drives a gear 137 mounted on the shaft 135. A pair of vertically aligned and vertically spaced shafts 138 are journalled in the gear casing 133 adjacent its upper end and these shafts carry within the gear casing gears 139 and 140, the gear 139 being driven from the gear 137 and the gear 140 being driven from the gear 139. The shafts 138 project beyond the front and rear sides of the gear casing 133 and carry chucks 141 at their ends which are used to releasably hold drills 142 or similar rotary wood working tools in place. It will be noted that two of the drills 142 project from the casing 133 towards the inner surface of the board J, while the other two drills project from the other surface of the gear casing 133 towards the other board K when the boards are clamped in place. The motor 132 is provided with an electrical switch 143 and an armored cable 144 carrying electrical conductors runs from a source of electric power to the switch 143 and thence to the motor 132.

A pair of clamps 145 are releasably secured to the lower wide outer flanges of the rails 17 and these clamps form bearings which project below the rails for reception of a shaft 146 extending transversely below the bed and having a lever 147 secured to its forward end. The carriage 130 has a pair of spaced lugs 148 projecting downwardly therefrom between the rails 17 and an arm 149 secured to the shaft 146 extends upwardly and projects between the two lugs 148. By swinging the lever 147, it will be seen that the carriage 130 and parts carried thereby may be slid longitudinally of the bed A. The carriage 130 has a transverse slot formed in its central portion and the carriage 131 has transversely spaced lugs 150 on its under surface which project into the transverse slot of the carriage 130. A shaft 151 extending longitudinally of the bed is journalled in ears 130

152 projecting downwardly from the carriage 130 and this shaft 151 carries an arm 153 which projects upwardly between the two lugs 150. An angularly bent lever 154 is secured to one end of the shaft 151 and projects forwardly beyond the forward side of the machine. An arcuate plate 155 is bolted to the carriage 130 adjacent the formed edge thereof and this plate is provided with a notch within which a dog 156 pivoted to the lever 154 is adapted to fit. A link 157 connects the dog 156 to a handle 158 of the bell crank lever type which handle is pivoted to the lever 154 adjacent its outer end and is pressed outwardly by a spring 159 to normally hold the dog 156 into engagement with the arcuate plate 155. It will be seen that as the outer end of the lever 154 is swung upwardly and downwardly, the carriage 131 may be slid forwardly and rearwardly transversely of the carriage 130 and bed A. When the dog 156 is in engagement with the notch on the plate 155, the carriage 131 will be so disposed that the gear casing 133 is centrally located relative to the boards J and K.

Although various type of stops may be used for limiting the sliding movement of both the carriage 130 and the carriage 131, there are illustrated in the drawings as best shown in Figs. 6 and 7, stops for this purpose. A bar 160 shaped as shown in Fig. 6, extends generally longitudinally of the machine and is secured at its left end to the standard 27 for the left pair of clamps B. This bar projects below the carriage 130 and is upwardly bent at its right end and carries therein a screw 161 adjustably locked in the bar 160 by a lock nut 162 and this screw 161 is adapted to strike the right end of the carriage 130 to limit the extreme longitudinal sliding movement of the carriage 130 toward the right end of the bed A. A screw 163 is mounted in the left end of the carriage 131 and this screw is adjustably locked in place on the carriage by means of a lock nut 164. The head of the screw 163 is adapted to contact the standard 27 to limit the extreme longitudinal sliding movement of the carriage 130 toward the left of the bed A. The carriage 131 can be freely slid forwardly and rearwardly on the carriage 130, when the carriage 130 is located in a general central position between the two extreme longitudinal stops. There is a pin 165 secured to the left end of the carriage 131 and projecting downwardly therefrom and this pin is adapted to ride between a pair of longitudinally spaced blocks 166 carried by the bar 160 after the drills 142 have been brought into contact with the board K and moved therein for some little distance. When the carriage 131 is positioned so that the pin 165 extends between the two blocks 166, longitudinal movement of the carriage 130 on the bed is limited in both directions by contact of the pin 165 with

the blocks 166. The pin 165 and the blocks 166 are located relative to each other so that the drills 142 may bore for some distance into the board K and the longitudinal movement of the carriage 130 will be only limited by engagement of the right end of the carriage with the stop 161 and by the engagement of the stop 163 with the standard 27. The blocks 166 will prevent sliding movement of the carriage 131 rearwardly beyond a point where the pin 165 contacts the forward surfaces of the blocks 166 unless the pin 165 is located midway between the two blocks 166. The blocks 166 will preferably be mounted on the bar 160 for sliding adjustment. Another pin 167 is secured to the carriage 131 adjacent the rear end thereof and projects upwardly therefrom. An angular bar 168 is secured to the standard 27 adjacent its rear side and this bracket carries spaced blocks 169 which cooperate with the pin 167 to limit longitudinal sliding movement of the carriage 130 within certain distances when the carriage 131 has been slid forwardly on the carriage 130 to bring the two forward drills 142 into engagement with the board J. The carriage 131 may be freely slid forwardly on the carriage 130 and the longitudinal sliding movement of the carriage 130 will not be limited by engagement between the pin 167 and the blocks 169 until the drills 142 have moved into the board J for some little distance, i. e. the carriage 130 may be longitudinally slid until the stop 161 engages the right end of the carriage 130 and until the stop 163 engages the standard 27, while the forward drills 142 are boring for a short distance into the board J. When, however, the pin 167 is located centrally relative to the two blocks 169, the carriage 131 may be transversely slid on the carriage 130 to permit the drills 142 to be carried entirely through the board J. By this construction, it will be seen that elongated shouldered openings may be cut through the two boards by the boring mechanism G.

The rectangular opening cutting mechanism H will now be described. This mechanism is best illustrated in Figs. 1, 3, 4, 10, 11, and 12. A longitudinally extending drive shaft 170 is journaled in the two bars 19 and 20 connecting the rails 17. An electric motor 171 is mounted on the floor 16 and this motor has a motor shaft 172 on which a pulley 173 is mounted. A belt 174 runs over the pulley 173 and over a pulley 175 mounted on the right end of the shaft 170. The motor 171 is controlled by a switch 176 which may be mounted on the carriage 26 and a flexible conduit 177 carrying electrical conductors runs from a suitable source of electricity to the switch 176 and thence to the motor 171. The shaft 170 carries six eccentrics 178 thereon, three of which are fixed on the shaft adjacent the left end of the same in closely spaced

relation and three of which are fixed to the shaft adjacent the right end of the same in closely spaced relation. A pair of central arms 179 have hubs at their lower ends mounted on two of the eccentrics 178 and one of the arms 179 is mounted on an eccentric 178 adjacent the left end of the shaft 170, and the other arm 179 is mounted on an eccentric 178 adjacent the right end of the shaft 170. The two arms 179 project upwardly above the shaft 170 and extend to a position between the two boards J and K as best shown in Fig. 3, so that the upper ends of the arms are at a level with certain portions of the boards J and K when these boards are clamped in position. The upper ends of the arms 179 are of T-shape and extend generally transverse to the shaft 170 and the machine. Received within grooves at the upper ends of the arms are short hatchet-like saw blades 180, each arm carrying one blade with the teeth thereof facing the board J and each arm carrying another blade having its teeth facing the other board K. A pair of front arms 181 have hubs which are journaled on two of the eccentrics 178 and one of the arms 181 is mounted on an eccentric 178 adjacent the left end of the shaft 170 and the other arm 181 is mounted on one of the eccentrics located adjacent the right end of the shaft 170. The arms 181 run upwardly to points adjacent but forwardly disposed from the position of the board J, when clamped in place and the upper ends of the arms 181 are grooved to receive small hatchet-like saws 182 similar to the saws 180. A pair of arms 183, similar to the arms 181, have hubs at their lower ends journaled on a pair of eccentrics 178, one arm 183 being mounted on an eccentric 178 adjacent the left end of the shaft 170 and the other arm 183 being mounted on one of the eccentrics adjacent the right end of the shaft 170. The arms 183 project upwardly to points rearwardly disposed from the position of the board K when clamped in place. The upper ends of the arms 183 are grooved to receive hatchet-like saws 184 which face the outer surfaces of the board K. The various hatchet-like saws 180, 182, and 184 are releasably clamped in the various arms by means of screws 185. With the construction described, it will be seen that extending upwardly from adjacent each end of the shaft 170, there are three arms and in each group of arms there is one central arm 179 and one side arm 181 and one side arm 183. The saws 182 and 184 of the arms 181 and 183 are so positioned relative to the saws 180 of the arms 179 that the saws 182 and 184 on arms 181 and 183 adjacent the left end of the shaft 170, are disposed slightly to the right of the saws 180 on the arm 179 adjacent the left end of the shaft 170. Similarly, the saws 182 and 184 on the arms 181 and 183 adjacent the right end of the shaft 170 are disposed slightly to the left of the saws 180 on the arm 179 mounted adjacent the right end of the shaft 170. The saws 182 and 184 on arms 181 and 183 adjacent the two ends of the shaft 170 are in transverse alinement. It will be seen that when the motor 171 is in operation, the arms 179, 181 and 183 and the saws carried thereby will be given an oscillatory movement. A pair of longitudinally spaced brackets 186 are mounted on the inner side of the rear rail 17 and a pair of arms 187 are pivoted at medial points to these brackets 186. The two arms 187 are interconnected by longitudinally extending upper and lower rods 188 and 189 respectively, and links 190 are pivoted on the upper rods 188 and are also pivotally connected to the two central arms 179. The arms 187 and the rods 188 and 189 form what may be called a pivoted central frame for swinging the upper ends of the arms 179 transversely of the machine to throw saws 180 respectively into engagement with the boards J and K. Secured to the outer sides of the two rails 17 and projecting horizontally outwardly therefrom are spaced brackets 191 which are pivotally connected to the lower ends of arms 192 interconnected by lower and upper bars 193 and 194 respectively, and forming what may be called side frames. The arms 192 at each side of the machine are interconnected at their upper ends by longitudinally extending rods 195 on which are pivoted links 196, which are also pivotally secured at their inner ends to the arms 181 and 183 respectively adjacent thereto. The arms 192 forming portions of the frame just described at the front side of the machine, are additionally interconnected by a rod 197. The arms 192 forming portions of the frame at the rear side of the machine, are additionally interconnected by the rod 198 and short inwardly projecting arms 199 secured to the arms 192 at the rear side of the frame are interconnected by a horizontal rod 200. It will be seen that the arms 181 and 183 can be inwardly swung in a transverse direction to carry the saws 182 and 184 mounted thereon into engagement with the boards J and K respectively, as the side frames just described are swung inwardly. The side frames are normally held in outwardly swung relation against stops 231 secured to the rails 17 by means of stiff springs 201 which are secured to the outer edges of the wide flanges of the rails 17 and project upwardly therefrom and bear against the bars 193. Accordingly, the saws 182 and 184 will normally be held out of engagement with the boards J and K in outwardly disposed relation therefrom.

Adjacent the various arms 179, 181 and 183, there is mounted on the rails 17 a longitudinally sliding carriage 202 consisting merely of a pair of transversely spaced horizontal bars having grooves in their under surfaces receiving the upper edges of the rails 17. The

two bars forming the carriage 202 carry diagonal transverse ribs on their upper surfaces projecting in opposite directions and forming guides for a transversely sliding carriage 203, which interconnects the two bars forming the carriage 202, so that these bars will slide together. The carriage 203 includes a pair of horizontal and longitudinally extending bars 203a grooved to receive the ribs on the bars of the carriage 202 and resting on these bars, and a central cross bar 203b interconnects the two bars 203a. The central cross bar 203b is notched at its lower edge to permit of transverse sliding movement of the carriage 203 respective to the carriage 202. An arm 204 is secured to the cross bar 203b and this arm is forked at its lower end to receive the rod 189 of the inner frame for swinging the arms 179. Also secured to the top surface of the bar 203b are angular bars 205 and 206 respectively, one of which is disposed outwardly from the rod 197 of the outer frame at the front side of the machine and the other of which is disposed outwardly from the rod 200 of the outer frame at the rear side of the machine. When the carriage 203 is disposed in central relation so that the arms 179 are centrally disposed between the two boards J and K, the two angular bars 205 and 206 will be disposed in oppositely spaced relation respectively from the rods 197 and 200, so that they will not contact these rods. Mounted on the bar 203b of carriage 203 and projecting upwardly therefrom between the position of the two boards J and K, is a standard 207 and this standard may be forked at its upper end as shown. An electric motor 208 is secured to the forked portion of the standard 207 above the position of the boards J and K and this motor is controlled by an electric switch 209 to which a flexible conduit 210 carrying electrical conductors extend. The motor 208 has a motor shaft 211 projecting vertically downwardly therefrom and a pair of horizontal and vertically spaced circular saws 212 are mounted on this motor shaft 211. Collars 213 mounted on the shaft 211 bear against the upper side of the upper saw 212 and against the lower side of the lower saw 212 respectively, and a spacing collar 214 is interposed between the two circular saws. The lower end of the shaft 211 is screw threaded and a jamb nut 215 is mounted on the lower end of the shaft 211 and removably secures the saws 212 and collars 213 and 214 in tightly assembled relation.

A rack 216 is bolted or otherwise secured to the rear rail 17 below the upper outwardly extending flange thereof and a bracket 217 is secured to the under side of the rear bar of the carriage 202 and projects downwardly therefrom to form a hub within which a shaft 218 is journaled for rotary and sliding movement. The shaft 218 carries a pinion 219 at

its inner end engaging with the rack 216 and the shaft is equipped with a wheel 220 at its outer end. A plate 216a is secured to the rack 216 and projects downwardly therefrom to retain the pinion 219 in engagement with rack 216 and to prevent outward sliding movement of shaft 218. By rotation of the wheel 220, the carriage 202 together with the carriage 203 and parts carried thereby may be slid longitudinally of the rail 17. Mounted on the rear bar of the carriage 202 and projecting upwardly therefrom is an angular bracket 221 which forms an apertured hub within which a shaft 222 is journaled. The shaft 222 carries a wheel 223 at its outer end and a collar 224 inwardly from the hub of bracket 221. Inwardly from the collar 224 the shaft 222 is screw threaded and works through a nut 225 mounted on the rear bar 203a of carriage 203. By rotation of the wheel 223, it will be seen that the carriage 203 together with the parts carried thereby may be slid transversely of the bed. Transverse sliding movement of the carriage 203 is limited by means of stops 226 extending in vertical relation from the rear and front edges of the carriage 202 and having screws 227 mounted therein adapted to engage the front and rear sides of the transversely sliding carriage 203. The screws 227 are adjustable in the stops 226 and are locked in place by means of jamb nuts 228. Longitudinal sliding movement of the carriage 202 is limited by means of two stops 229 mounted on the front rail 17 in spaced relation from the central position of the ends of the bars 203a of the carriage 203. When the carriage 203b is centrally disposed relative to its limits of transverse movement, longitudinal sliding movement of the carriage 202 and, accordingly, of the carriage 203 is limited in both directions by contact of the ends of the stops 229 with the ends of the front bar 203a. Carried by the stops 229 are screws 230 which are adapted to contact the ends of the carriage 202 to limit the extreme sliding movement of this carriage when the carriage 203 has been transversely slid to such a point that the ends of the stops 229 will be disposed either at one side of the front bar 203a or at the other side thereof. Screws 230 are adjustably locked in place by jamb nuts 230a.

In Figs. 13, 14, and 15, there is illustrated a window frame jamb K formed by use of the present machine. This jamb has at its left end a groove c extending transversely across the inner face of the jamb and adapted to be cut by the groove cutting mechanism C of the present machine. At its right end, the jamb K has a groove d cut therein and extending generally transversely of the jamb in the inner face of the jamb, but inclined toward the left end of the jamb from the lower edge of the jamb as shown in Fig. 13 to the upper edge of the jamb, the groove d is adapted to

be formed by the groove cutting mechanism D. At the two ends of the jamb K, there are notches E and F cut in the lower edge of the jamb. These notches are adapted to be cut by the notch cutting mechanisms E and F respectively. Adjacent the left end of the jamb K, there are provided a pair of pulley receiving openings g which pulley receiving openings are adapted to be cut by the boring mechanism G. It will be noted that these pulley receiving openings are shouldered at their ends on the inner face of the jamb K. Adjacent the right end of the jamb K there is found a rectangular opening h for receiving the sash weights of a window frame and this opening is adapted to be cut by the rectangular opening cutting mechanism H. It will be noted that the ends of this rectangular opening h are shouldered inwardly from the inner face of the jamb K. The machine of the present invention is not only adapted to form the grooves c and d, notches e and f, pulley receiving openings g and rectangular sash weight receiving openings h in a jamb K which will be used as the left jamb for a sash frame, but the machine of the present invention is also adapted to cut similar grooves, notches and openings in a right hand jamb J, which will match with the jamb K to form the right hand jamb for a sash frame in which the jambs may be assembled. The grooves c of the jambs are adapted to receive the tenons formed at the ends of a header in the sash frame, while the notches e are adapted to receive projecting shoulders at the edge of the inner ends of the header. The grooves d are adapted to receive tenons formed at the ends of the sill of the sash frame, while the notches f are adapted to receive shoulders formed at the inner ends of the edges of the sill. The sash weight pulleys of the window frame are adapted to be received within the pulley receiving openings g, while strips closing the sash weight receiving openings h are adapted to be received in these openings.

Operation

Prior to use of the machine, a number of boards cut to proper length for use as the jambs of window sash frames will be placed near the machine. The motors 47, 48, 101, 102, 132, 171 and 208 will then be set in operation to cause the circular and gullet saws 57-59, 58-60, the rack saws 113-114, and the circular saws 121 to be rapidly rotated and to cause the drills 142 to be rapidly rotated and the hatchet-like saws 180, 182 and 184 to be rapidly oscillated. The machine will preferably be controlled by two operators, one of whom will stand at the front side of the machine and will control the sliding rod 82 and the levers 147 and 154 and the other of whom will stand at the rear side 65 of the machine and will control the two

wheels 220 and 223. A pair of boards J and K will be clamped in place in oppositely disposed spaced parallel relation by the various clamps B. The operator at the front side of the machine will then grasp the handle 70 85 and slide the rod 82 against the tension of the spring 84 to the right, thereby closing the switch 78 and causing the motor 77 to be set in operation. The motor 77 will then operate until the gears 91 and shafts 90 have 75 been carried through 180°, whereupon the motor 77 will be shut off, as has been previously described. As the shafts 90 are rotated through 180°, the carriages 45 and 46 will be either carried downwardly through 80 their length of movement, or will be carried upwardly through their length of movement and the saws 57-59, and the saws 58-60 will be carried into engagement with and across the ends of the two boards J and 85 K to cause the grooves c and d to be made in the boards. At the same time that the carriages 45 and 46 are slid upwardly or downwardly, the carriages 99 and 100 will be slid transversely of the carriages 25 and 26 to 90 cause the rack saws 113 and 114 to be engaged with and carried across the ends of the lower edges of the boards J and K to cut the notches E and F in the boards.

After the operator at the front side of the machine has slid the rod 82 to the right, he may give his entire attention to the boring mechanism G. He will grasp the lever 154 and the handle lever 158 with one hand and the lever 157 with his other hand. As the handle lever 158 is pressed toward the lever 154, the dog 156 will be carried out of engagement with the notch in the arcuate plate 155 and the outer end of the lever 154 may then be swung upwardly to slide the carriage 131 on the carriage 130 towards the rear side of the machine. The drills 142 extending towards the rear side of the machine will then be brought into engagement with the board K and the lever 147 will then be swung first toward one end of the machine, then toward the other end of the same to cause the carriage 130 to ride longitudinally back and forth on the rails 17. The lever 154 will be maintained in continued upwardly swung relation to maintain the drills 142 facing toward the rear side of the machine in engagement with the board K. Considering that the drills 142 are first engaged with the board K when the lever 147 is swung as far to the right end of the machine as possible, the right end of the carriage 130 will engage the stop screw 161 and the drills can only be carried into the board K for a short distance or until the pin 165 engages the front face of one of the blocks 166. As the lever 147 is swung toward the left end of the machine, the drills 142 will cut into the board K to form the shoulders of the openings g toward the right end of the board K. When the pin 165 is 130

carried over the left front corner of the right hand block 165, the drills 142 will be carried further into the board K to form the central openings or slots of the openings *g*, whereupon the pin 165 will strike the right end surface of the left hand block 166. The lever 154 will then be swung downwardly slightly to carry the pin 165 around the right forward corner of the block 166, whereupon as 10 the lever 147 continues to be swung to the left, the drills 142 will cut the shoulders at the left end of the opening *g* in the board K. Preferably the lever 147 will also be swung toward the right end of the machine, so that 15 all portions of the openings *g* may be smoothly cut. The cutting of the openings *g* in the board K is a continuous operation and takes but a few seconds. After the openings *g* of the board K are cut, the lever 154 is swung 20 downwardly, whereupon the drills 142 projecting toward the forward side of the machine will be brought into engagement with the board J and the openings *g* in this board may be cut in similar manner, the pin 167 25 acting with the blocks 169 in exactly the same manner as did the pin 165 with the blocks 166 in the previous operation. Of course, the screws 161 will engage the right side of the carriage 130 and the heads of the screws 30 163 will engage the standard 27 to limit the extreme length of shoulder cuts of the openings *g*. As the screws 161 and 163 may be adjusted, it will be seen that the length of shouldered cuts may be varied. The spacing 35 between the two blocks 166 and the spacing between the two blocks 169 will determine the length of cut of the central slots of the openings *g* and as the blocks 166 may be held in different positions on the bar 160, and as 40 the blocks 169 may be held in different positions on the bar 168, it will be seen that the length of the central slots of the openings *g* may be varied. After the openings *g* have 45 been cut in both boards J and K, the boring mechanism G will be slid to central position between the two boards J and K by operation of the lever 154 and the handle lever 158 will be released to permit the dog 156 to again engage with the notch of the arcuate plate 50 155.

At the same time that the operator at the front side of the machine is causing the mechanisms C, D, E, F and G to cut the grooves *c*, *d*, the notches *e*, *f*, and the pulley 55 receiving openings *g* in the two boards J and K, the operator at the rear side of the machine will cause the rectangular opening cutting mechanism H to cut the rectangular openings *h* in the two boards. The original 60 position of the hatchet-like saws 180, 182 and 184 and the circular saws 212 relative to the boards J and K will be as shown in full lines Fig. 10, as the two boards J and K are clamped in place by the clamps B. The operator 65 at the rear side of the machine after the

boards are clamped in position, will first rotate the wheel 232 as in a counter clockwise direction looking towards the wheel as the operator faces the same. This will cause the screw portion of the shaft 222 to be threaded outwardly from the nut 225 to thereby cause the carriage 203 to slide on the carriage 202 toward the front side of the machine. As this is done, the forked arm 204 which engages the rod 189, will swing the inner frame formed by the arms 187 and rods 188 and 189 to carry the upper end of the frame toward the rear side of the machine and thus to cause the links 190 to swing the central arms 179 toward the board K and then cause the hatchet saw 214 projecting toward the board K to be carried into engagement with the same to make the extreme end cuts in the board K extending into the board from the inner face thereof. Also as the carriage 203 is slid toward the front side of the machine on the carriage 202, the angular bar 206 will engage the rod 200 to swing the upper end of the outer frame at the rear side of the machine formed by the arms 192, bars 193 and 194 and rods 195 and 198 and 200 inwardly to thereby cause the links 196 pivotally secured to the outer arms 183 to move inwardly toward the outer side of the board K. The hatchet-like saws 184 will then be carried into engagement with the outer side of the board K and as these saws are oscillating they will quickly make the end cuts of the rectangular opening *h* in the board K which end cuts extend inwardly into the board from the outer face thereof. As the carriage 203 moves toward the forward side of the machine, and at the same time that the rearwardly projecting saws of the central arms 179 are carried into engagement with the inner face 90 of the board K and the saws 184 of the outer arms 183 are carried into engagement with the outer face of the board K, the circular saws 212 will be brought into engagement 95 with the inner face of the board J. The wheel 220 will be rotated to cause the gear 219 to engage the rack 216 and thereby slide the carriage 202 together with the carriage 203, standard 207, motor 208 and circular saws 212 longitudinally of the bed A and thereby cause the circular saws 212 to make the longitudinal extending side cuts of the opening *h* in the board J. The relative positions of the various saws 180, 182, 183 and 212 during this first cutting action is illustrated in Fig. 11, the circular saws 212 being shown in their extreme right hand position in full lines and extreme left hand position in dotted lines. It will be observed that when the saws 180 of the central arms 179 are in engagement with the board K, it is possible to move the circular saws 212 through their extreme movement without causing the circular saws to come into engagement with the forwardly facing saws 180 on the central 100 105 110 115 120 125 130

arms 179. The stop screws 230 will limit the sliding movement of the carriage 202 longitudinally of the rails 17 by contact with the ends of the carriage 202 when the various hatchet-like saws are in the position illustrated in Fig. 11. In this position the stops 229 cannot engage the bars 203a of the transversely sliding carriage 203 to limit movement of the carriages in a longitudinal direction between these stops. It will, however, be seen that the stops 229 will limit longitudinal sliding movement of the carriages 202 and 203, so that the circular saws 212 cannot come in contact with the central arms 179 and the saws 180 carried thereby unless the arms 179 have been swung to such a position as shown either in Fig. 11, or in Fig. 12, where certain of the saws 180 are in engagement with one of the boards J or K. In other words, the front bar 203a of the carriage 203 can only move beyond the stops 229 in either transverse direction to bring the same into engagement with the stop screws 230 when the central arms 179 and the saws 180 carried thereby are so positioned that the circular saws 212 cannot engage the arms 179 or the saws 180 carried thereby. The stops 229 are, therefore, provided to make the machine fool proof. After the longitudinal side cuts for the rectangular opening 8 have been made in the board J, the wheel 220 will be rotated until the carriage 203 is located in the central position relative to the stops 229, whereupon the wheel 223 may be rotated in a clockwise direction to thread the screw portion of the shaft 222 into the nut 225 and thereby slide the carriage 203 toward the rear side of the machine on the carriage 202. As this is done, the angular bars 206 are disengaged from the rod 200 and the spring 201 at the rear side of the machine bearing against the bar 193 of the outer frame located at the rear side of the machine, will swing the said frame to its original position, thereby drawing the saws 184 of the arms 183 out of engagement with the board K and at the same time the inner frame actuated by engagement between the arm 204 and the rod 189 will swing the central arms 179 to carry the rearward saws 180 carried thereby out of engagement with the board K. As the wheel 223 is continuously rotated in a clockwise direction, the forward saws 180 on the arms 179 will be swung into engagement with the board J to make the end cuts of the opening h which project into the board from the inner face thereof. The angular bracket 205 will also engage the rod 197 to swing the outer frame at the front side of the machine inwardly and thereby cause the outer arms 181 to be moved toward the board J to engage the hatchet-like saws 182 with the outer surface of the board J and thereby make the outer end cuts for the opening h in the board J.

As the carriage 203 slides toward the rear side of the machine, the circular saws 212 will be brought into engagement with the board K and by rotation of the wheel 220 the two carriages 202 and 203 may be moved longitudinally of the rails 17 to make the longitudinal side cuts of the opening h in the board K. After all the cuts in the two boards have been made in this manner, the carriage 203 will be slid to central position relative to the two boards J and K. Although the movements of the mechanism H are quite complicated to produce the various cuts for making the openings h in the two boards J and K, the two openings may be cut in the boards in very short order by rapid manipulation of the two wheels 220 and 223, only.

After the various mechanisms have been manipulated as described, the various clamps B can be released from engagement with the boards, whereupon the boards J and K can be removed from the machine and the material filling the rectangular openings h of the two boards may be readily knocked out. The two boards J and K will then form completed right hand and left hand jambs for a window frame.

As the mechanisms C and E are mounted on the carriage 25, it will be seen that these mechanisms can be variably spaced from the right end of the machine by applying a wrench to the head of the shaft 39 and thus rotating the shaft to cause the pinion 40 to move over the rack 37. The bracket 86 can also be slid longitudinally of the rail 17 and as the gear 92 is mounted on the shaft 87 for sliding movement in the slot 87a of this shaft, it will be seen that mechanisms C and E may be operated from any position to which they may be slid on the rails 17. The longitudinal position of the boring mechanism G can also be varied and the position of the brackets 145 within which the shaft 146 is mounted, can be varied longitudinally of the rail 17. It is thus possible to adjust the machine for making jambs of various lengths. Numerous other adjustments to vary the length of the openings g produced, and of the rectangular openings h as well as the angular inclination of the grooves c and d may also be made. Different types of saws may be substituted for the circular and gullet saws 57-59 and 58-60, and for the rack saws 113 and 114 to produce different types of cuts in the boards worked on. The spacing between the circular saws 122 may be varied if desired, or other types of saws may be substituted for these circular saws. Although the machine is primarily intended for use in making the necessary cuts in a pair of boards to produce both the right and left hand jambs for window sash frames, it will be readily understood that the various mechanisms illustrated and described can be used for other purposes. Although the vari-

ous mechanisms C, D, E, F, G and H are adapted for conjoint operation on a pair of boards clamped in fixed position, it will be understood that any or all of these various 5 mechanisms are adapted for individual operation irrespective of the other mechanisms.

The machine of the present invention has been amply demonstrated in actual practice and has been found to be successful for the 10 purposes intended. It has heretofore been necessary to use a number of different machines for making the necessary cuts to produce jambs similar to the jambs J and K for window frames and it has been necessary to 15 change the position of the boards worked on often while the various cuts are being made. With the present machine, the boards need only be once clamped in place and all the necessary cuts may be made in the same for 20 producing the jambs, while they are clamped in fixed position. The labor and time saved in producing the jambs by use of the present machine is great. With the present machine, a pair of boards may be clamped in 25 the machine and all the necessary cuts made in the boards to produce finished window jambs and the boards removed from the machine in less than two minutes.

It will, of course, be understood that 30 various changes may be made in the form, details, arrangement and proportions of the various parts without departing from the scope of the present invention.

What is claimed is:—

35 1. A machine for rapidly producing the jambs for window sash frames, having in combination a bed, means for clamping a board in fixed relation to said bed, a mechanism mounted on said bed for cutting a pulley receiving opening through the board and mechanism for cutting notches adjacent the two ends of the board in one edge thereof to receive the sill and header of a sash frame, all of said mechanisms being adapted 40 for conjoint operation on said board while it is held in fixed relation by said clamping means.

50 2. A machine for rapidly producing the jambs for window sash frames, having in combination a bed, means for clamping a board in fixed relation to said bed, a mechanism mounted on said bed for cutting a sash weight receiving opening through the board adjacent one end of the same and mechanisms mounted on said bed for cutting notches adjacent the two ends of the board in one edge thereof to receive the sill and header of the sash frame, all of said mechanisms being adapted for conjoint operation 55 on the board while it is held in fixed relation by said clamping means.

60 3. A machine for rapidly producing the jambs for window sash frames, having in combination a bed, means for clamping the board in fixed relation to said bed, mecha-

nisms mounted on said bed for cutting grooves extending generally transversely to the board to receive the ends of the sill and header of a window sash frame and mechanisms mounted on said bed for cutting notches adjacent the two ends of the board in one edge thereof to receive the sill and header of the frame, all of said mechanisms being adapted for conjoint operation on said board while it is held in fixed relation by 70 said clamping means.

4. A machine for rapidly producing the jambs for window sash frames, having in combination a bed, means for clamping a board in fixed relation to said bed, mechanisms mounted on said bed for cutting grooves extending generally transversely to the board to receive the ends of the sill and header of a window frame, mechanisms mounted on said bed for cutting notches adjacent the two ends of the board in one edge thereof to receive the sill and header of the frame and means for operating said second mentioned mechanisms respectively from said first mentioned mechanisms, said first mentioned and last mentioned mechanisms being adapted for successive operation on the board while the board is fixedly clamped by said clamping means.

5. A machine for rapidly producing the jambs for window sash frames, having in combination a bed, means for clamping a board in fixed relation to said bed, a mechanism mounted on said bed for cutting pulley receiving openings through the board adjacent one end thereof, a mechanism mounted on said bed for cutting a sash weight receiving opening through the board adjacent the other end of the same, mechanisms mounted on said bed for cutting notches adjacent the two ends of the board in one edge thereof to receive the sill and header of a sash frame, all of said mechanisms being adapted for conjoint operation on said board while it is clamped in fixed relation by 100 said clamping means.

6. A machine for rapidly producing the jambs for window sash frames, having in combination a bed, means for clamping a board in fixed relation to said bed, a mechanism mounted on said bed for cutting a sash weight receiving opening through the board adjacent one end of the same, mechanisms mounted on said bed for cutting grooves extending generally transversely to the board to receive the ends of the sill and header of a window sash frame, and mechanisms mounted on said bed and operating in synchronism with said last mentioned mechanisms for cutting notches adjacent the two ends of the board in one edge thereof to receive the sill and header of a sash frame, all of said mechanisms being adapted for conjoint operation on said board while it is held in fixed relation by 105 said clamping means.

7. A machine for rapidly producing the jambs for window sash frames, having in combination a bed, means for clamping a board in fixed relation above said bed, a mechanism mounted on said bed for cutting pulley receiving openings through the board adjacent one end thereof, a mechanism mounted on said bed for cutting a sash weight receiving opening in the board adjacent the other end of the same, mechanisms mounted on said bed for cutting grooves extending generally transversely to the board, adjacent the ends of the same to receive the ends of the sill and header of a sash frame and mechanisms mounted on said bed for cutting notches adjacent the two ends of the board in one edge thereof to receive the sill and header of a sash frame, all of said mechanisms being adapted for conjoint operation on said board while it is clamped in fixed relation by said clamping means.
8. A woodworking machine having in combination, means for clamping a pair of boards in parallel oppositely disposed spaced relation, a carriage mounted for sliding movement both parallel to said boards and normal to the planes of said boards between said boards, rotary cutting means mounted on said carriage and having portions projecting toward the positions of said two boards respectively, means mounted on said carriage for driving said rotary cutting means, means for sliding said carriage in a direction normal to the planes of said boards and means for sliding said carriage in a direction parallel to said boards.
9. The structure defined in claim 8, stops limiting the movement of said carriage parallel to said boards, and stops limiting the movement of said carriage normal to the planes of said boards.
10. The structure defined in claim 8, stops limiting the extreme movement of said carriage parallel to said boards, stops limiting the movement of said carriage normal to the planes of said boards when said carriage is disposed adjacent said first mentioned stops, and stops limiting movement of said carriage parallel to said boards when said carriage is generally centrally disposed relative to said first mentioned stops.
11. A machine for rapidly and consecutively producing similar right hand and left hand cuts in a pair of boards having in combination, means for clamping a pair of boards in spaced parallel oppositely disposed fixed relation, a cutting mechanism mounted for movement between a pair of boards clamped in place by said clamping means, said cutting mechanism including rotary cutting tools projecting towards both boards and means for moving said cutting mechanism to operate first on one of said boards to cut into the inner face thereof and then to operate on the other of
- said boards to cut into the inner face thereof.
12. A machine for rapidly and consecutively producing similar right hand and left hand cuts in a pair of boards having in combination, a bed, means for clamping a pair of boards in spaced parallel fixed relation to said bed, a cutting mechanism mounted on said bed for operation between said boards and for sliding movement on said bed both normal to said boards and parallel thereto said cutting mechanism including rotary cutting elements projecting toward the respective boards at opposite sides of the cutting mechanism and means for sliding said cutting mechanism normal to said boards to first bring one of said cutting elements into engagement with one of said boards and then to bring the other of said cutting elements into engagement with the other of said boards and means for sliding said cutting mechanism parallel to said boards whereby opposite elongated recesses and openings may be cut into said boards.
13. A woodworking machine having in combination, a bed, means for clamping a pair of boards in parallel spaced relation to said bed, a carriage mounted on said bed between the positions of said boards for sliding movement parallel to said boards and for sliding movement normal to said boards, a pair of cutting tools mounted on said carriage and projecting respectively in opposite direction towards said two boards, means carried by said carriage for driving said cutting tools, operating means for sliding said carriage normal to said boards to permit engagement of one cutting tool with the inner face of first one of said boards and to permit engagement of the other of said cutting tools with the inner face of the other of said boards and operating means for sliding said carriage parallel to said boards when said cutting tools are in engagement with the same.
14. A woodworking machine having in combination, a bed, means for clamping a pair of boards in spaced parallel fixed relation on the said bed, a carriage mounted on said bed for sliding movement parallel to said boards and for sliding movement normal thereto, a motor mounted on said carriage, a standard mounted on said carriage and disposed between the position of said boards, a rotary cutting tool journaled on said standard and having cutting elements projecting at opposite sides of said standard towards said respective boards at approximately the same level as portions of said boards, means for driving said shaft from said motor and operating means for sliding said carriage normal to said boards to throw the cutting elements at one side of said standard first into engagement with the inner surface of one of said boards and then to throw

the cutting elements at the other side of said standard into engagement with the inner surface of the other of said boards and operating means for sliding said carriage parallel to said boards to move said cutting elements longitudinally of said boards when in engagement therewith.

15. A woodworking machine having in combination, a bed, means for clamping a pair of boards in spaced parallel fixed relation to said bed, a carriage mounted on said bed for sliding movement parallel to said boards and normal thereto, a motor mounted on said carriage, a standard mounted on said carriage between said boards, a shaft journaled in said standard and disposed at a level even with the level of portions of said boards, means for driving said shaft from said motor, said shaft extending normal to the general planes of said boards, spindles carried by the two ends of said shaft, rotary cutting tools carried by said two spindles and projecting respectively towards said boards, operating means for sliding said carriage parallel to said boards and operating means for sliding said carriage normal to said boards.

16. The structure defined in claim 15, and stops confining sliding movement of said carriage within defined limits.

17. A woodworking machine having in combination, a bed, means for clamping a pair of boards in spaced parallel fixed relation to said bed, a carriage mounted on said bed for sliding movement parallel to boards clamped by said clamping means, a second carriage mounted on said first carriage for sliding movement normal to said boards, a cutting mechanism mounted on said second carriage between the positions of said boards and including cutting elements projecting respectively towards said two boards, means carried by said second carriage for driving said cutting mechanism, operating means for sliding said first carriage parallel to said boards and operating means for sliding said second carriage normal to said boards.

18. A woodworking machine having in combination, means for clamping a pair of boards in fixed parallel spaced relation, an upwardly extending guide mounted adjacent said clamping means, a carriage upwardly and downwardly slidable on said guide, a circular saw mounted on said carriage for movement upwardly and downwardly between said boards and for engagement with said boards, means for driving said saw mounted on said carriage and means for moving said carriage upwardly and downwardly on said guide.

19. The structure defined in claim 18, and means for counterbalancing the weight of said carriage and the parts carried thereby

as said carriage moves upwardly and downwardly on said guide.

20. The structure defined in claim 18, said last mentioned means comprising a motor, a shaft driven from said motor, a crank secured to said shaft and a connecting rod pivoted to said crank and carriage.

21. The structure defined in claim 18, said last mentioned means comprising an electric motor, a shaft driven from said motor, a crank secured to said shaft, a connecting rod pivoted to said crank and carriage, a switch for actuating said motor, and means for holding said switch in closed position after it has been once closed until said shaft has been rotated through 180° and then for opening said switch.

22. A woodworking machine having in combination, a bed, means for clamping a pair of boards in fixed parallel spaced relation to said bed, an upwardly extending guide secured to said bed, a carriage mounted on said guide for upward and downward travel, a circular saw mounted on said carriage and extending between the positions of said boards for engagement with said boards to cut grooves therein as said carriage is raised and lowered, a second carriage mounted for sliding movement below said boards on said bed in a plane normal to said boards, a rack saw carried by said second carriage, means mounted on said second carriage for driving said rack saw and connecting means between said first mentioned carriage and said second carriage for moving said second carriage to carry said rack saw into contact with and across the edges of said boards as said first mentioned carriage is raised and lowered without interference with the action of said circular saw.

23. A woodworking machine having in combination, a bed, means for clamping a pair of boards in fixed parallel spaced relation to said bed, an upwardly extending guide mounted on said bed, a first carriage mounted on said guide for upward and downward travel, a cutting mechanism including rotary cutting elements mounted for rotation on said first carriage and adapted for movement between two boards held by said clamping means to cut grooves therein, a second carriage mounted on said bed for sliding movement normal to said boards below the same, a cutting mechanism mounted on said second carriage and including a rotary cutting element adapted to engage and move across the edges of boards held in place by said clamping means as said second carriage is slid, means on said second carriage for rotating said cutting element, means for raising and lowering said first carriage, an arm pivoted to said guide, an arm carried by said first carriage, rollers mounted on said second mentioned arm at one side of the pivot of said first arm, said first mentioned

5 arm extending between said rollers and a pitman connecting the lower end of said first mentioned arm with said second carriage, whereby as said first carriage is raised, said second carriage will be slid to cause said rotary cutting element carried thereby to be thrown into successive engagement with the edges of said boards and carried there across as said first carriage is slid.

16 24. A woodworking machine having in combination, a drive shaft having an eccentric portion thereon, means for rotating said shaft, means for clamping a pair of boards in oppositely disposed parallel relation near said drive shaft and in parallel relation thereto, an arm pivotally mounted on the eccentric portion of said drive shaft and having a free end projecting between the positions said boards will assume when clamped by said clamping means, a pair of hatchet-like saws secured to said arm and respectively projecting from opposite sides thereof towards the positions of said boards and means for swinging said arm to first throw one of said saws into engagement with the inner face of one of said boards and then to throw the other of said saws into engagement with the inner face of the other of said boards.

25 25. A woodworking machine having in combination, a drive shaft having eccentric portions thereon, means for rotating said drive shaft, means for clamping a pair of boards in oppositely disposed parallel spaced relation near said drive shaft and in parallel relation thereto, a pair of side arms pivotally mounted on respective eccentric portions of said drive shaft and having free ends disposed respectively outwardly from the positions of said two boards when clamped in place, inwardly facing hatchet-like saws carried by said arms at their free ends and means for swinging said arms to carry the respective saws secured thereto into engagement with the outer surfaces of adjacent boards.

35 26. A woodworking machine having in combination, a drive shaft having eccentric portions thereon, means for clamping a pair of boards in fixed parallel spaced relation above said shaft, a pair of arms pivotally connected at their lower ends to respective eccentric portions of said shaft and extending to points level with certain portions of said boards, hatchet-like saws carried at the upper ends of said arms, the respective arms being outwardly disposed at their upper ends from the positions of respective boards and means for throwing one of said saws into engagement with one of said boards while the other of said saws is held out of engagement with the other of said boards and for throwing the second saw into engagement with the other of said boards while the first saw is held out of engagement with the first board.

35 27. A woodworking machine having in combination, a drive shaft having eccentric

portions thereon, means for rotating said drive shaft, means for clamping a pair of boards in oppositely disposed parallel spaced relation near said drive shaft and in parallel relation thereto, a central arm pivoted on one of the eccentric portions of said drive shaft and having a free end extending between the positions that said boards will assume when held by said clamping means, a pair of outer arms pivoted on eccentric portions of said drive shaft and respectively having free ends disposed outwardly from the positions of the outer sides of said boards when clamped in place, a pair of oppositely disposed hatchet-like saws carried at the free end of said central arm and respectively projecting in opposite directions towards the inner sides of said boards, hatchet-like saws carried at the free ends of said side arms and projecting respectively towards the outer sides of respective boards and means for swinging said central arm and said side arms on said drive shaft to cause one saw carried by said central arm and the saw carried by one of said side arms to be first engaged with the opposite sides of one of said boards and then to cause the other saw of said central arm and the saw carried by the remaining side arm to be carried into engagement with the opposite sides of the other of said boards.

28. The structure defined in claim 27, the saws on said side arms being longitudinally spaced from the saws of said central arm relative to the direction of extension of said boards when clamped in place.

29. A woodworking machine having in combination, a drive shaft having eccentric portions thereon, means for clamping a pair of boards in parallel spaced relation above said drive shaft, a central arm pivoted at its lower end to one of the eccentric portions of said drive shaft and projecting upwardly between the positions of said boards, outwardly extending and oppositely disposed hatchet-like saws carried at the upper end of said central arm, a pair of side arms also pivoted at their lower ends to eccentric portions of said drive shaft and projecting upwardly to points outwardly disposed when the positions of said respective boards, inwardly extending hatchet-like saws mounted at the upper ends of said side arms and means for swinging said three arms to cause one of the saws of said central arm and one of the saws carried by a side arm to be first engaged with one of said boards and then to cause the other saw of said central arm and the other saw carried by the remaining side arm to be engaged with the other of said boards.

30. A woodworking machine having in combination, a bed, means for clamping a pair of boards in fixed parallel spaced relation to said bed, a drive shaft journaled in said bed, and mounted parallel to the position that said boards will assume when clamped

by said clamping means, an arm eccentrically mounted on said drive shaft for oscillatory movement, said arm having a free end projecting between said boards, outwardly extending and oppositely disposed hatchet-like saws secured to the free end of said arm and means for swinging said arm to first throw one of said saws into engagement with the inner side of one of said boards and then to throw the other of said saws into engagement with the inner side of the other of said boards.

31. A woodworking machine having in combination, a bed, a shaft journaled in said bed, means for rotating said shaft, means for clamping a pair of boards in parallel spaced relation to said bed and parallel to said shaft, a central arm eccentrically mounted on said shaft for oscillatory movement and having a free end projecting between the positions that a pair of boards held by said clamping means will assume, outwardly projecting and oppositely disposed hatchet-like saws carried at the free end of said central arm, side arms eccentrically mounted on said shaft for oscillatory movement and having free ends projecting respectively to points outwardly disposed from the outer sides of the two boards clamped by said clamping means, inwardly facing hatchet-like saws carried by said last mentioned arms and means mounted on said bed for swinging said central arm and said side arms to first throw one saw on said central arm and the saw on one of said side arms into engagement respectively with opposite surfaces of one of said boards and to then throw the other saw on said central arm and the saw on the other of said side arms into engagement respectively with opposite surfaces on the other of said boards.

32. A woodworking machine having in combination, a drive shaft, having eccentric portions thereon, means for clamping a pair of boards in oppositely disposed parallel spaced relation near said drive shaft, and in parallel relation to said drive shaft, a central arm pivoted at one end to an eccentric portion of said drive shaft and projecting to a point between the positions that said boards will assume when clamped in place, a pair of outer arms pivoted to eccentric portions of said drive shaft and respectively projecting to points outwardly disposed from the respective positions of said two boards, hatchet-like saws carried at the free end of said central arm and projecting outwardly therefrom in oppositely disposed relation, inwardly extending hatchet-like saws carried at the free ends of said side arms, means for swinging the free end of said central arm to throw the respective saws carried thereby into engagement with the inner sides of respective boards, resilient means normally holding said side arms with the saws carried thereby outwardly disposed from engagement with the

outer sides of said boards and means operating as said central arm is swung towards one of said boards to carry the saw on one of said side arms into engagement with the outer side of the same board and similar means operating as said central arm is swung towards the other of said boards to carry the saw on the other of said side arms into engagement with the outer side of the said other board.

33. A woodworking machine having in combination, a bed, means for clamping a pair of boards in fixed parallel spaced relation to said bed, a carriage mounted on said bed for sliding movement both normal to said boards and parallel to said boards, a standard mounted on said carriage, a circular saw journaled on said standard, means for driving said circular saw, said circular saw being disposed between the positions of said two boards, means for sliding said carriage normal to said boards to carry said circular saw first into one of said boards and then into the other of said boards and means for sliding said carriage parallel to said boards to cause said circular saw to make long cuts in said boards when engaged with the same.

34. The structure defined in claim 33, stops limiting the sliding movement of said carriage normal to said boards, and stops limiting the sliding movement of said carriage parallel to said boards.

35. A woodworking machine having in combination, a long bed, means for clamping a pair of boards in parallel spaced relation to said bed and parallel to the length of the bed, a shaft journaled in said bed and extending longitudinally thereof, means for rotating said shaft, an arm eccentrically connected to said shaft for oscillatory movement and having a free end disposed between the positions of said boards, a pair of outwardly projecting and oppositely disposed cutting tools carried at the free end of said arm and extending transversely relative to said bed, a carriage mounted on said bed for sliding movement both longitudinally thereof and transversely thereof, a cutting mechanism mounted on said carriage and including rotary cutting elements located between the positions of said boards and projecting towards both boards, means for driving said cutting mechanism, means for sliding said carriage transversely of said bed to cause the cutting elements projecting towards respective boards to be engaged with the inner sides of the same, means for sliding said carriage longitudinally of the bed to cause the cutting elements engaged with the respective boards to make long cuts in the same and means operating as said cutting elements are engaged with one of said boards to swing said arm to carry the cutting tool projecting at one side thereof into engagement with the

other of said boards and to carry said arm and the tools carried thereby out of the way of said cutting mechanism as said carriage is longitudinally slid on said bed, said last mentioned means operating as said cutting elements are engaged with the other of said boards to swing said arm to carry the cutting tool projecting at the other side thereof into engagement with the first of said boards and to carry said arm and the tools carried thereby out of the way of said cutting mechanism as said carriage is longitudinally slid on said bed.

36. A woodworking machine having in combination, means for clamping a pair of boards in oppositely disposed parallel spaced relation, an oscillating arm extending between the positions of said boards and mounted for swinging movement normal to said boards, a pair of oppositely disposed cutting tools mounted on said arm and projecting respectively towards the inner sides of said boards, a circular saw disposed between the positions of said boards and mounted for both movement normal to said boards and parallel thereto, means for moving said circular saw normal to said boards to carry the same first into engagement with one of said boards and then into engagement with the other of said boards, means for moving said circular saw longitudinally of said boards to make long cuts in the same when in engagement therewith and means operating as said circular saw is moved normal to said boards into engagement with one of said boards to swing said arm toward the other of said boards to carry one of said cutting tools into engagement therewith and at the same time to withdraw said arm and the tools carried thereby out of the path of said circular saw as it is moved longitudinally of the board with which it is engaged.

37. A woodworking machine having in combination, means for clamping a pair of boards in oppositely disposed parallel spaced relation, a pair of oscillating side arms extending to positions respectively outwardly disposed from respective boards and mounted for swinging movement towards said boards, resilient means urging said arms to outwardly swung position relative to said boards, inwardly projecting cutting tools carried by said arms for engagement with said boards, a circular saw disposed between the positions of said boards and mounted for both movement normal to said boards and parallel thereto, means for moving said circular saw normal to said boards to carry the same first into engagement with one of the boards and then into engagement with the other of the boards, means for moving said circular saw longitudinally of the boards to make long cuts in the same when in engagement therewith and means operating as said circular saw is moved normal to said boards

into engagement with one of the same to swing the arm outwardly disposed from the other of the boards to carry the tool mounted thereon into engagement with the other of said boards.

38. A woodworking machine having in combination, a bed, clamping means for securing a pair of boards in fixed spaced parallel relation to said bed, an oscillating arm extending between the positions of said boards and mounted for swinging movement normal to said boards a pair of oppositely disposed hatchet-like saws carried by said arm and projecting respectively toward the inner sides of respective boards, a carriage mounted on said bed for sliding movement normal to said boards and parallel thereto, a circular saw mounted on said carriage and disposed between the positions of said two boards, means for sliding said carriage normal to said boards to carry said circular saw first into engagement with one of said boards and then into engagement with the other of said boards, means for sliding said carriage parallel to said boards to cause said circular saw to make long cuts in the boards when in engagement therewith and means operating as said circular saw is moved normal to said boards into engagement with one of said boards to swing said arm toward the other of said boards to carry one of said cutting tools into engagement therewith and at the same time to withdraw said arm and the tools carried thereby out of the path of said circular saw as it is moved longitudinally of the board with which it is engaged.

39. A woodworking machine for cutting rectangular openings in a pair of boards having in combination, a long bed, means for clamping a pair of boards in parallel relation to said bed and in oppositely disposed spaced parallel relation to each other, a pair of interconnected central arms mounted for oscillatory movement and extending between the boards to points longitudinally spaced from each other, means for oscillating said arms, said arms being mounted for swinging movement normal to the bed, pairs of outwardly disposed hatchet-like saws carried by said arms for engagement with the inner sides of said boards, a carriage mounted on said bed for sliding movement normal to the bed and longitudinally thereof, a pair of spaced circular saws mounted on said carriage and disposed between the positions of said boards, said circular saws extending at right angles relative to said hatchet-like saws, means for sliding said carriage normal to said bed to carry said circular saws first into engagement with one of said boards and then into engagement with the other of said boards between said two arms, means for sliding said carriage longitudinally of said bed to cause said circular saws to make long spaced parallel cuts in the boards with which the

- saws are engaged and means operating as said circular saws are carried into engagement with one of said boards by sliding movement of said carriage normal to said bed,
- 5 to swing said arms toward the other of said boards to carry the hatchet-like saws projecting toward the same into engagement therewith and at the same time to withdraw said arms and the saws carried thereby out
- 10 of the path of said circular saws as they are moved longitudinally of the board with which they are engaged.
40. A woodworking machine for cutting rectangular openings in a pair of boards having in combination, a long bed, means for clamping a pair of boards in oppositely disposed spaced parallel relation to each other on said bed and parallel to said bed, pairs of interconnected side arms located at the two
- 15 sides of said bed and extending upwardly to points outwardly disposed from said two boards, the arms in each pair being longitudinally spaced relative to each other, said arms being mounted for swinging movement to
- 20 and from the boards adjacent thereto, means for oscillating said arms, means for holding said arms under resilient tension in outwardly disposed relation from respective boards, hatchet-like saws secured to said arms and
- 25 inwardly disposed therefrom for engagement with the outer sides of said boards, a carriage mounted on said bed for sliding movement normal to the bed and longitudinally thereof, a pair of spaced circular saws
- 30 mounted on said carriage and disposed between the positions of said boards, said circular saws extending at right angles relative to said hatchet-like saws, means for driving said circular saws, means for sliding said carriage
- 35 normal to said bed to carry said circular saws first into engagement with one of said boards and then into engagement with the other of said boards, means for sliding said carriage longitudinally of said bed to cause said circular saws to make long spaced parallel cuts in the boards with which the saws are engaged and means operating, as said carriage is slid normal to said bed to carry said circular saws into engagement with one of the
- 40 boards, to swing the pair of arms at one side of the bed toward the other of said boards and to carry the hatchet-like saws mounted thereon into engagement with the other said board.
- 45 55. In testimony whereof I affix my signature.
- CARL A. JOHNSON.
